PRODUCTION OF PROFILED SECTIONS
FROM SHEET METAL BY ROLLING

Emil Penkala, London, England, assignor to Metal Trim Limited, London, England, a British company

Application June 19, 1937, Serial No. 149,217
In Great Britain June 29, 1936

2 Claims. (Cl. 153—28)

This invention relates to the production of profiled sections and tubes by rolling from sheet metal, and has among its objects to obviate or to reduce to a minimum stretching of the material in the longitudinal direction, for instance at the edges or marginal parts of the section, which stretching is liable to result in the formation of waves or corrugations which are difficult to eliminate in subsequent operations, to reduce to a minimum lateral stretching of the material and consequent further thinning of the same at the corners or bent parts of the section, and generally to enable profiled sections to be produced with a comparatively low rolling pressure whereby the size of the rollers, diameter of the spindles carrying the same, and the power employed may be very substantially reduced.

In the method usually employed for the production of profiled sections by rolling from sheet metal, the rollers of each pass are profiled so as to correspond exactly to the profile of the section at the particular position. It has, however, been proposed to profile the rollers so that the material is gripped by the rollers at or adjacent the edges or marginal parts of the section and is left substantially free at the corner or bend. In this prior proposal the application of the pressure at the edges or marginal parts would tend to increase the usual longitudinal stretching action. It has also been proposed to profile the rollers in such manner that the pressure is confined to the corner or bent portion of the section. In such an arrangement pressure on the longitudinally stretched parts is avoided, but inasmuch as the pressure is concentrated on the laterally stretched parts at the bend or corner, such lateral stretching, with its accompanying thinning of the metal, would be increased.

According to the present invention the profiled sections are produced by rolling from sheet metal by passing the metal between rollers which are profiled so that the pressure of the rollers on the material is confined to intermediate parts of the section which are not stretched or subject to stretching during the profiling operations.

More specifically, the invention embraces a method wherein the rolling pressure is applied at and confined to parts of the section at which there is no, or substantially no, tendency to longitudinal or lateral stretching, the pressure preferably being confined to positions adjacent the bend or bends in the section, but not at such bend or bends. Thus, no part of the section liable to stretching, either longitudinally or laterally, is subject to pressure which would tend

to increase such stretching with its accompanying thinning of the metal.

In order to eliminate any grooving or line marking of the section by the application of the localized pressure according to the invention, and also to ensure true rolling of the section walls or flanks, the regions of pressure in successive passes are arranged at different positions in the walls or flanks of the section so as to overlap. Thus, any grooves or lines resulting from the localized pressure in one pass will be eliminated in a succeeding pass.

Preferably each pass, i. e., each individual profile formation or stage, is duplicated or multiplied so that while the material is in any one formation or stage of formation it is subject to at least two rolling pressures localized at different overlapping parts of the section wall or walls. A further and important advantage of applying the pressure in overlapping stages as described is that true rolling of the desired profile can be effected with a very much lower rolling pressure than was heretofore possible and thus the rollers and their spindles may be of lighter construction and the power required for operation also is lower.

The invention is hereinafter described by way of example with reference to the accompanying diagrammatic drawing, in which—

Figure 1 is a cross-sectional view showing one stage in the formation of an L section by the method according to the invention and illustrating the manner in which the rollers preferably are profiled for this purpose;

Figures 2 to 4 are similar views illustrating stages in the formation of a U or tubular section; and

Figures 5 to 8 are similar views illustrating successive stages in the formation of a U or channel section according to a modification of the aforesaid method.

In carrying the invention into effect according to one embodiment and with reference more particularly to Figure 1 of the accompanying diagrammatic drawing, the metal strip 1 is passed between the profiled rollers 2, 3 by which it is bent to the section shown. In order to localize the rolling pressure at intermediate positions, i. e., positions remote from the lateral edges of the strip which are subject to longitudinal stretching, and also from the bend in the strip where the metal is subject to lateral stretching, the upper roller 2 is shaped so that the roller profiles at the parts between which the walls or flanks of the section are disposed are non-parallel and

diverge as indicated by the angle α degrees in a direction away from the bend in the strip. Thus, no pressure is applied at the edges of the strip. The lower roller 3 is formed with a circumferential groove or recess 3a so as to avoid any application of pressure at or immediately adjacent the bend in the strip.

In Figure 1 the rolling pressure is localized substantially at the parts a of the metal strip. 10 This localized pressure not only avoids any intensification of longitudinal stretching at the edges of the strip during the profiling operation, but tends to compensate for any such stretching that may occur, inasmuch as the localized pressure acting near the bend in the section tends to cause a certain amount of elongation of the metal strip at the bend and by suitable design of the rollers any stretching at the edges may be neutralized entirely by the said elongation at 20 the bend. Furthermore, as the inclined faces of the upper roll 2 act in a downward direction on the strip, the localized pressure tends to upset the metal towards the bend and thus neutralizes any tendency to thinning of the metal 25 at this point.

As shown in Figures 2 to 4, a U or tubular section is produced by passing between successive pairs of rollers 4, 5, 6, 7 and 8, 9, the upper roller 30 in each case being shaped similarly to the roller 2 in Figure 1 so that the pressure on the section is localized at the parts a .

The application of localized pressure in the manner described renders it possible to produce profiled sections with a very much lower rolling 35 pressure than was heretofore possible, but such localized pressure sometimes results in the formation of slight grooving or line-marking of the section. In order to overcome such grooving or line-marking, while at the same time retaining 40 the advantages resulting from the use of a comparatively low rolling pressure, the localized pressure is in successive passes exerted or laterally displaced and overlapping portions of the metal strip.

45 As shown in Figure 5, which illustrates a first stage in the formation, for example, of a U or channelled section, the upper roller 10 is shaped on the inclined sides so that the pressure on the walls or flanks of the section 1a is localized at 50 the parts a as before described. The roller 10 is formed with a centrally disposed circumferential groove or recess 10a so that the pressure on the central portion of the section is localized at the parts a^1 . The same result may be secured by 55 providing a centrally disposed circumferential groove or recess 11a in the lower roller 11 or, if desired, both rollers may be provided with the grooves.

60 In the next pass, as shown in Figure 6, the upper roller 12 is formed with two circumferential grooves or recesses 12a each of which is of less width than the width of the pressure region a^1 in Figure 5 so that the pressure on the central 65 portion of the section is localized at the part a^2 which overlaps the parts a^1 in the preceding pass. The lower roller 13 likewise may be provided with circumferential grooves or recesses 13a, in which case the grooves 12a may be dispensed with.

70 In the next pass, as shown in Figure 7, the upper roller 14 is formed with a centrally disposed circumferential groove or recess 14a the width of which is less than the width of the pressure region a^2 in Figure 6, whereby the rolling 75 pressure on the central portion of the section is

localized at the parts a^3 which overlap the part a^2 in the preceding pass. If desired, the lower roller 15 in this pass also may be formed with a centrally disposed groove or recess corresponding to the groove or recess 14a.

5 In the final pass, as shown in Figure 8, the rollers 16, 17 may be profiled to correspond to the final profile of the section 1a.

Preferably all the upper rollers are relieved in the manner described with reference to Figure 10 1 so that the pressure on the section walls or flanks is applied at the parts a adjacent the bend or corner. If desired, however, the upper rollers may be relieved in any other suitable manner for the same purpose.

15 The application of the localized pressure in overlapping stages as described with reference to Figures 5 to 8, in addition to eliminating line-marking or grooving, also facilitates upsetting of the metal into or towards the corner or bend in 20 the section to compensate for the natural thinning tendency due to the lateral stretching. Obviously, by applying the localized pressure in overlapping stages the metal may be upset towards the bend or corner with a comparatively 25 low pressure on the rollers, and such upsetting may serve to increase the thickness of the section at the bend or corner.

The invention may be carried into effect by the use of rollers suitably relieved or recessed to 30 avoid the application of pressure at any parts subject to stretching or which have been stretched longitudinally or laterally, or rollers in accordance with my copending application Serial Number 149,219, filed June 19, 1937, advantageously are employed, it being understood that although a slight relieving of the rollers is sufficient for the purpose, recesses of substantial depth are permissible.

35 The invention, while being of general application in the rolling of profiled sections from sheet metal, is particularly applicable for use in connection with the rolling method and apparatus according to my prior application Serial Number 149,216, filed June 19, 1937, and according to my further co-pending applications Serial Numbers 149,218 and 149,220, both filed June 19, 1937.

What I claim and desire to secure by Letters Patent is:

1. A method for the production of profiled sections from sheet metal by bending the metal along one or more longitudinal lines, in such manner that there is a tendency for the metal to stretch laterally in one or more zones containing the lines of bend and to stretch longitudinally in zones laterally remote from said lines, with substantially no tendency to stretch in any direction in neutral zones of substantial area located between the first mentioned and second mentioned zones, said method comprising the application of 50 rolling pressure exclusively to said neutral zones by squeezing the metal of said neutral zones in sufficient degree to cause a slight thinning thereof.

55 2. The method set forth in claim 1, characterized by repeating the operation one or more times so that the profile of the metal is altered step by step under successive rolling pressure applications and so that in successive rolling applications the neutral zones to which pressure is applied are laterally displaced so as to be overlapped edgewise on the corresponding neutral zone or zones of the preceding operation.

CERTIFICATE OF CORRECTION.

Patent No. 2,146,223.

February 7, 1939.

EMIL PENKALA.

It is hereby certified that the above numbered patent was erroneously issued to "Metal Trim Limited" as assignee of the entire interest therein whereas said patent should have been issued to --Emil Penkala, of London, England, assignor of one-half interest to Metal Trim Limited, of London, England, a British company--, as shown by the record of assignments in this office; and that the said Letters Patent should be read with this correction therein that the same may conform to the record of the case in the Patent Office.

Signed and sealed this 9th day of October, A. D. 1945.

Leslie Frazer
